PAPER RULING MACHINE

Charles E. Clarke, Winchester, and Robert T. Duffy, Boston, Mass., and Joseph W. Cloutier, Franklin, N. H., assignors to Lindbladh Corporation, Boston, Mass., a corporation of Massachusetts

Original application July 31, 1939, Serial No. 287,552. Divided and this application October 8, 1940, Serial No. 360,272

6 Claims. (Cl. 33—34)

This invention relates to ruling machines of the type in which sheets of paper are conveyed on a wide cloth belt beneath pens arranged to be raised and lowered to rule lines on the sheets in accordance with predetermined patterns. The present application is a division of our co-pending application Ser. No. 287,552 filed July 31, 1939, in which appears a complete and detailed description of the entire ruling machine. Since the present application relates particularly to the drive for the ruling machine, reference should be had to the above-mentioned application for the organization of the machine as a whole.

The primary object of our invention is to increase the output of ruling machines. These machines as heretofore constructed have been limited to a speed which will not produce efficiently more than four reams of ruled paper per hour. One of the problems to be solved in the production of a speedier machine arises from the necessity for an improved drive which is flexible, capable of minute regulation, and free from backlash and vibration.

Another object of our invention is to eliminate the system of change gears universally used on previous machines and which necessitated the provision of a large stock of gears which had to be stored near the machine and used to replace some of the gears on the machine when it was desired to set up the machine for a different rate of production or for different sizes of sheet.

One of the important features of the invention resides in the combination of a base slidably mounted in the frame of the machine and a motor and a pump for operating the mechanism for feeding the sheets into the machine. A variable speed transmission unit, for example of the Reeves type, disposed on the motor shaft and belted to a pulley running on a driving shaft of the machine provides a change speed system whereby the speed of the machine may be varied with perfect flexibility by sliding the motor base back and forth within the frame.

Another feature of the invention consists in a novel system of shafting and gearing by means of which the pen controlling mechanism may be directly regulated by changing the position of the motor base. Further, an independent change gear system is permanently disposed between the main drive shaft and the cloth roll, whereby the speed of the cloth roll can be regulated without effecting the rate of the pen controlling mechanism.

The provision of separate drives for the cloth roll and for the pen controlling mechanism re-

sults in a machine capable of almost infinite variation as to rate of feed and size of sheet, and one which is relatively free from backlash and vibration.

Our invention will be best understood and appreciated from the following description of a preferred embodiment thereof, selected for purposes of illustration and shown in the accompanying drawings, in which:

Fig. 1 is a view in side elevation showing the general organization of the ruling machine,

Fig. 2 is a view in perspective of the driving mechanism,

Fig. 3 is a view in cross section showing the gearing for the cam shafts, and

Fig. 4 is a view in perspective showing the drive for the cloth roll.

Although, as above stated, reference should be had to our co-pending application for a detailed understanding of the organization of the ruling machine of our invention, we shall present a brief outline of its general construction before proceeding to describe the subject matter of the invention claimed herein. The machine is supported by and partially contained within a rectangular metal frame 10 considerably longer than it is wide. By means of the mechanism not shown herein but including a driven feed tape, the sheets of paper are taken from a stack and advanced one by one on the surface of a cloth belt 86 to a gate 94 where each sheet is momentarily checked and straightened. The sheets are then successively conveyed on the cloth belt beneath pens held by transverse clamps which are lowered and raised in accordance with the length of the lines to be ruled on each sheet. After the sheets pass from beneath the pens, they are carried under a heater to dry the ink and finally removed at the far end of the machine and delivered into a receiving bin.

The improved drive of our invention is best shown in Fig. 2, in which it will be seen that a flat L-shaped base 14 is grooved to fit over a cylindrical cross girt 12 in the lower part of the machine frame and has an arm 16 which is hooked at its outer end to fit over another cross girt 12. A threaded socket in the base 14 receives a threaded rod 18 which extends out through the frame and is held against longitudinal movement by a pair of collars 20, only one of which appears in the drawings. Fast on the outer end of the rod 18 is a hand wheel 22, and it will be seen that rotation of the hand wheel and rod draws the base 14 back and forth on the cross girts 12. Bolted securely to the base 14 are a motor 24 and a pump 28. The pump is

driven from the motor by a belt 26 and operates the suction wheel of a feeding mechanism, through the flexible suction hose 29. On the outer end of the motor shaft is a Reeves transmission device which comprises a pair of disks 30 having opposed convex faces. The outer disk is keyed to the motor shaft and free to slide longitudinally upon it, being urged toward the other disk by a heavy spring 34. The inner disk 30 is fixed to the motor shaft. A belt 32 is held between the disks 30 and drives a large pulley 36 which rotates freely on a stub shaft 38 journalled in a bearing bracket 40 secured to the frame 10 and in the near wall of a housing 42 secured to the outside of the frame 10. A clutch 44 controlled by a lever 46 serves to couple the pulley 36 to the stub shaft 38.

Fast on the stub shaft 38 adjacent the pulley 36 is a pinion 48 which drives a large gear 50 secured on a shaft 52 journalled in a bearing bracket 54 and in the housing 42, best seen in Fig. 1. Within the housing 42 and secured to the shaft 52 is a gear (not shown) in mesh with another gear 56 secured to a shaft 58 journalled in the housing 42 and in a bearing bracket and gear housing 60 which is secured to the frame 10. The shaft 58 runs longitudinally of the frame 10, and by means of bevelled gears in the housing 60, motion of the shaft 58 is transmitted to a shaft 62 which runs transversely across the frame 20 and is journalled in a housing 64 secured to the frame on the ruler's side of the machine. For sake of convenience the shaft 52 may be termed the main drive shaft and the shaft 62 may be termed the cam shaft.

As seen in Fig. 3, the cam shaft 62 carries a gear 71 which directly drives gears 72 and 74 on stub shafts 66 and 68 and also drives a gear 76 on a third stub shaft 70. In the latter case the drive from the gear 71 is transmitted through an idler gear 78. In Fig. 1 I have designated the pen beams and their standards collectively by the reference character 80 and this includes part of the mechanism for raising and lowering the pens, all as will more fully appear in our co-pending application referred to above. Fast on the stub shafts 66, 68 and 70 are cam disks 82 carrying dogs 83 which serve to raise and lower the pen beams. Contained within the upper portion of the frame 10 is a curved bed 84 over which travels the wide cloth belt 86. At the front end of the machine the cloth passes around a roll 88 which is driven in a manner to be described hereafter. At the rear end of the machine the cloth passes over an idler roll 104.

Fast on the outer end of the shaft 62 is a cam 90 which operates a lever 92 to rock a gate 94. Periodically the gate is lowered into contact with the cloth 86 and serves to check each sheet momentarily and to straighten it.

It will now be evident from the description of the mechanism that the cam shaft 62 is driven from the main drive shaft 52 and drives the cams which raise and lower the pens and pen beams 80 and control the gate 94. The speed of the cam shaft is regulated by manipulating the hand wheel 22 to slide the motor and its base along the cross girts 12. As the motor approaches the pulley 36, the belt rides up on the convex surfaces of the disks 30 and increases its speed. Since each sheet must be checked by the gate 94, it will be apparent that the number of sheets being ruled in a given time is equal to the number of revolutions of the shaft 62 during the same time. It likewise follows that for

each revolution of the shaft 62 the cam disks 82 must also make a complete revolution. Therefore, the rate of production of the machine is directly regulated by the hand wheel 22.

5 The size of the sheet to be ruled must control the speed of the cloth, since for each revolution of the shaft 62 an amount of cloth equal to the length of the sheet must be driven under the gate and the pens. It follows that once the rate of production of the machine has been established by manipulation of the hand wheel 22, means must be provided for adjusting the rate of travel of the cloth.

To these ends we provide on the shaft 52 a series of gears of different diameters suggested at 53 and contained within the housing 42. Another gear (not shown) is carried on the end of a pivoted lever 96 which may be moved to bring the gear into engagement with any one of the gears 53 on the shaft 52. The gear on the lever 96 is constantly in mesh with a gear (not shown) coupled to a shaft 98, which appears in Fig. 4. A housing 100 contains bevelled gears which transmit the motion of the shaft 98 to a series of gears in a casing 102 fastened to the inside of the frame 10. The last gear in the series is fast to a shaft journalled in the frame 10 and carrying the cloth roll 88. The cloth roll shaft is geared to a shaft 106 carrying an upper or feed roll (not shown). On the outer end of the shaft 106 is a hand wheel 108 by means of which the cloth roll 88 may be turned when the machine is being set up for operation.

It will now be seen that by shifting the lever 35 96 the rate of the shaft 98, and thus the rate 35 of the cloth roll 88, may be varied. Thus we have eliminated the necessity for providing replacement gears, and the operator of the machine is not forced to remove a gear from the machine 40 and replace it with another each time the size 40 of the sheet is changed, but only has to shift the lever 96. The drive for the pen controlling mechanism and the gate is entirely separate 45 from the drive for the cloth roll, an arrangement which eliminates backlash and promotes efficiency of ruling.

The pump 28 supplies a vacuum for operating a feeder of the type disclosed in U. S. Letters Patent No. 2,205,921 issued to Charles E. Clarke on June 25, 1940, a flexible hose 29 being connected to the pump. It will be evident that the movement of the base 14 does not disrupt the operation of the pump 28 or vary its rate. A shaft 108 coupled to the shaft 58 by means of a universal joint 110 controls the operation of the timing mechanism of the feeder, and a shaft 112 coupled to the end of the shaft 98 by means of a universal joint 114 operates the conveying tape of the feeder. It will, therefore, be seen that the

60 pump 26 is arranged for constant and continuous operation, the timing mechanism for the feeder is driven by the drive for the pen controlling mechanism and the gate, and that the cloth roll drive also operates the feeder tape which brings the sheets to the cloth roll. Thus, in the general organization of the machine, regulation of the rate of the drive for that part of the mechanism which controls the rate of production of the machine is unified, whereas an independent drive jointly operates the sheet conveying mechanisms of the feeder. The result is that one setting of the hand wheel 22 effects all the changes which accompany a change in the rate of production of the machine, and one setting of the lever 96 automatically takes care of

all the adjustments necessary when the size of the sheet is to be changed. The simplicity of these adjustments is of tremendous importance in practical ruling, since the most important part of the ruler's work is to set up the machine before running through the work to be done. A machine capable of a satisfactory rate of production would not be advantageous, if it required a setting up operation that was long and complicated.

Having thus described our invention what we claim as new and desire to secure by Letters Patent of the United States is:

1. In a paper ruling machine including a frame and mechanism for feeding, conveying, and ruling sheets of paper; the combination of a base supported for sliding movement by the frame, a motor secured to the base, an air pump on said base connected to the feeding mechanism and driven by said motor, a Reeves transmission secured to the shaft of the motor and driving the ruling and the conveying mechanism, and means for sliding the base back and forth in the frame, whereby the speed of the ruling and conveying mechanism can be varied.

2. In a ruling machine including pen controlling mechanism, sheet conveying mechanism, and a vacuum operated sheet feeding mechanism, the combination of a motor, a pump driven directly from said motor and supplying the vacuum for the feeding mechanism, a Reeves transmission driven by said motor and driving the pen controlling mechanism, and a change speed gear system driven by the Reeves transmission and driving the sheet conveying mechanism.

3. In a ruling machine including a frame, pen controlling mechanism, sheet conveying mechanism, and a vacuum operated feeder, the combination of a base slidably carried on the frame, a motor secured to said base and having a shaft, a pump for the feeder also secured to the base and driven by said motor, a Reeves transmission carried on the motor shaft and driving the pen controlling mechanism and the sheet conveying mechanism, whereby the speed of the last mentioned mechanisms may be varied by sliding the base on the frame without affecting the rate or operation of the pump.

4. In a ruling machine including a frame, a

sliding base supported by the frame, a motor secured to the sliding base, a main drive shaft disposed at one side of the frame and driven from said motor, means between the motor and the shaft for changing the rate of revolution of the shaft, pen-controlling mechanism geared to said shaft, a sheet conveyor driven from said shaft, and means between the shaft and the conveyor for regulating the rate of the conveyor independently of the pen-controlling mechanism.

5. In a ruling machine including a frame, pen-controlling mechanism, sheet conveying mechanism, and sheet feeding mechanism; a base slidably supported by the frame, a motor and a pump secured to said base, a suction connection included in the feeding mechanism and operated by said pump, a main drive shaft mounted for rotation adjacent one side of said frame and driven from said motor, means between the motor and the shaft for varying the rate of rotation of the shaft responsive to the position of the base in the frame, means geared directly to the shaft for actuating the pen-controlling mechanism, a change speed gear system secured to said shaft and driving said sheet conveying mechanism, whereby movement of the base changes the rate of all the mechanisms except the pump and regulation of the change speed gear system varies the rate of the sheet conveyor without affecting the rate of the pen-controlling mechanism.

6. In a ruling machine the combination of a frame, a motor slidably mounted on the frame, a shaft mounted for rotation at one side of the frame and driven from the motor, means between the motor and the shaft for regulating the rate of revolution of the shaft responsive to the position of the motor on the frame, pen-controlling means geared to said shaft, a series of gears of different diameters secured to said shaft, sheet conveying means, a system of gears arranged to drive said sheet conveying means, and means for selectively engaging one of the gears on the shaft with the system of gears driving the sheet conveying means.
